[57] CLAIM

The ornamental design for bearing housing, substantially as shown and described.

DESCRIPTION

FIG. 1 is a end elevational view of my design for a bearing housing;

FIG. 2 is a top plan view thereof;

FIG. 3 is a bottom plan view thereof;

FIG. 4 is a side elevational view thereof; and

FIG. 5 is a perspective view thereof.

*Fig. 2.**Fig. 1.**Fig. 3.**Fig. 5.**Fig. 4.*
